SOUND RECORDING APPARATUS

Hugh A. Howell, Berwyn, Ill., assignor to Frank Raffles, Chicago, Ill.

Application March 25, 1940, Serial No. 325,766

2 Claims. (Cl. 274—13)

This invention relates to sound recording and reproducing apparatus in general and more particularly such apparatus as is used for making disc type phonograph records and for reproducing the sound recorded on such records. In its more specific aspects this invention is concerned with the means for making a disc type sound record.

One class of machines for making disc type sound records consists of a cutting stylus mounted at the end of a swinging arm which is so arranged in relation to a turn table upon which the recording disc is located that the arm moves radially at a rate which bears a fixed relationship to the rate of rotation of the turn table. To effect this type of motion there is provided a speed reducing gearing interconnecting the recording arm with the turn table. Such apparatus requires high accuracy in manufacture and is, therefore, quite expensive. Such apparatus cannot be readily and economically changed to effect a different speed relationship between the radial movement of the arm and the angular movement of the turn table. For some types of recording it is advisable that such change may be readily made. For instance, for recording speech it is quite possible to make the grooves in the disc type record very close together, thereby producing a comparatively long playing record. On the other hand, for recording music, particularly orchestral music, a greater spacing of grooves is desirable in order to allow for the production of the necessary high range of volume. It is one of the objects of the present invention to provide a mechanism for moving the tone arm radially of the turn table in such a manner that changes in rate of speed can be readily effected.

It is a further object of the present invention to provide a recording apparatus having a grooved record guiding disc so located with respect to the record cutting head that the grooves in the guiding disc can not possibly become clogged by shavings from the record being formed.

The attainment of the above and further objects of the present invention will be apparent from the following specification taken in conjunction with the accompanying drawing forming a part thereof.

In the drawing:

Figure 1 is a plan view of a sound recording and sound reproducing apparatus embodying the present invention;

Figure 2 is a sectional view taken along the line 2—2 of Figure 1; and

Figure 3 is a bottom plan view of the turn table of Figure 1.

Reference may now be had more particularly to Figures 1 and 2 of the drawing. The operating mechanism is mounted on a plate 1 that is secured to a cabinet 2 in any desired manner, as by a number of screws 3. A constant speed electric motor 4 is mounted on the underside of the plate 1, and through a suitable speed reducing gearing 5 turns a driving pulley 6 which is in engagement with the rim 7 of a turn table 8 that is mounted on the plate 1 for rotation about an axis 9 comprising a stationary circular pin. The turn table 8 rests upon a boss 10 which includes a thrust bearing for the turn table. The turn table may be removed bodily from the plate 1 by lifting the turn table vertically. The turn table includes a record receiving top surface 13 and has an off center pin 14. A disc type record 15 may be placed upon the surface 13. The record 15 has a central hole through which the pin 9 passes, and has another hole through which the pin 14 passes, thus positively holding the record against shifting upon the turn table. The record disc 15 may be of any of the well known types of thermo-plastic or other smooth material adapted to have a sound groove formed therein and sufficiently strong for a very large number of playbacks. The record disc is not pre-grooved.

A guiding disc 18 of brass or other metal is removably secured to the underside of the turn table 8 in any desired manner, as by a plurality of screws 19 that thread into holes in the rim of the turn table, with the heads of the screws lying in countersunk holes in the guiding disc 18. The guiding disc 18 has a spiral groove 20 formed on the bottom or exposed surface thereof. This spiral extends from a point 22 a short distance from the center of the disc to a point 23 adjacent the outer periphery of the disc. The disc 18 has a central hole 25 of a diameter exceeding that of the boss 10 so that the disc 18 is not required to bear any of the thrust of the weight of the turn table. To remove and replace the disc 18 it is merely necessary to lift the turn table, thus removing the turn table from the plate 1. It is then a simple matter to unscrew the screws 19.

An electro-magnetic cutting head 30 or sound impressing head, of a well known construction and having a cutting needle 31, is provided for cutting a spiral sound groove into the record 15 and impressing that sound groove with a sound track. The electric cutting head or record impressing head 30 is mounted at the end of an angle bracket 31 pivoted at 32 to a support 33.

The support 33 has a circular shaft 34 secured thereto and extending into a bushing 35 provided with a thrust bearing 36 so that the support may be oscillated about the axis of the shaft 34.

A U-shaped guiding arm 40 is pivoted at 41 to the support 33 and carries a guiding pin or needle 42 at one end, said pin being removably secured by a screw 43. The opposite end of the U-shaped arm 40, indicated at 45, extends up to and terminates adjacent the bracket 31. A leaf spring 46 is secured to the underside of the support 33 by a screw 47 and bears at its free end 48 against the arm 40, constantly urging the arm to rotate about its pivot 41 in a clockwise direction to maintain the needle 42 in engagement with the spiral groove 20 on the guiding disc 18. When the cutting head 30 is lifted away from the record receiving surface of the turn table by pivotal action of the bracket 31 about the pivot 32, the first small upward movement of the cutting head is of no effect upon the end 45 of the arm 40. This provides a small amount of lost motion in a vertical direction between the cutting head 30 and the guiding arm 40. After the needle 31 has been elevated a small amount, of the order of one-quarter or one-eighth of an inch, a further upward movement of the cutting head 30 causes the end 50 of the bracket 31 to engage the end 45 of the arm 40 and swing the same in a counter-clockwise direction about the pivot 41, and against the tension of the leaf spring 46. This causes the needle 42 at the end of the arm 40 to move out of engagement with the guiding disc 18. The support 33 may then be turned about the shaft 34 as a center to bring the cutting head out of position over the turn table and thus permit insertion or removal of a record 15 upon the turn table. Likewise, when the cutting head 30 is moved from the dotted line position shown in Figure 1 to the full line position, the cutting head 30 is maintained elevated above the turn table by an amount such that the needle 42 is maintained below and out of contact with the guiding disc 18. As the cutting head is lowered to bring the needle 31 into engagement with a record 15, this lowering action causes the end 50 of the bracket 31 to permit the spring 46 to swing the arm 40 to bring the needle 42 into engagement with the disc 18.

An explanation will now be given of the manner of forming a sound track upon the record disc 15. The electric motor 4 is started to rotate the turn table. Thereafter the cutting head 30 is positioned over the disc 15 and lowered so that the needle 31 engages the disc. This operation brings the needle 42 into engagement with the spiral groove 20 of the guiding disc 18. Rotation of the turn table causes the needle 42 to ride in the spiral groove 20 and thus turn the support 33 to move the cutting head 30 radially of the turn table as the record 15 is being rotated. The needle 31 thus cuts a spiral groove in the disc 15 which spiral groove is of the same pitch as the preformed spiral groove 20 in the guiding disc 18. At the same time the needle 31 is caused to vibrate, electro-magnetically, by amplified voice currents that are transmitted to the coil of the cutting head by conductors 55. The needle 31 thus forms the sound record in the groove as the groove is being cut in the record disc. When the cutting head is lifted, a counterbalancing spring 37 becomes effective to hold the head in its elevated position. The tension on the spring may be adjusted by an adjusting screw 38.

In the preferred arrangement the sound track

is formed in the record disc 15 as a spiral from the inside to the outside of the disc, the spiral 20 on the guiding disc 18 being preferably formed in that manner in relation to the direction of rotation of the turn table. As the turn table 8 rotates, and the needle 31 cuts its sound track in the record 15, the cuttings or shavings of the disc 15 tend to turn radially inwardly of the groove being cut. Since the cutting head is being moved radially outwardly it is constantly being moved away from the shavings formed by it, thus eliminating the need of a brush or the like for sweeping the shavings out of the path of the cutting needle 31. It is, of course, within the purview of the present invention to form the spiral groove 20 in such a relation to the direction of rotation of the turn table that the groove is cut in the record disc 15 from the outside towards the inside of the disc, if desired.

It is to be noted that the position of the guiding disc 18 is such that the groove 20 therein cannot become clogged by shavings or cuttings from the disc 15. This is a distinct advantage in that it thus permits the use of a guiding disc 18 of materials which can be worked in a simple manner. Also, it permits the formation of the grooves closer together without danger that thin shavings from the disc 15 will clog the guiding spiral 20.

The disc 18 may be readily removed and replaced by a different disc having a spiral 20 of a greater or lesser number of turns per inch radially of the disc. It has been found that for making records of the spoken voice the grooves of the spiral 20 may be much closer together than is possible for making records of music, where the volume and frequency range is greater. Thus if a record is to be made of spoken words a guiding disc 18 can be used wherein the grooves are closer together than in the case of a guiding disc used to guide the recording head 30 when recording music. As a result, a longer playing record is produced. By means of the present invention the guiding disc 18 can readily be replaced by one having a greater or lesser number of turns per inch of length, as required for recording speech or recording music, as the case may be.

The spiral groove 20 on the disc 18 is of a width and number of turns somewhat in excess of the maximum width or number of turns of a recording groove to be formed on a record 15. The innermost turn 22 of the spiral 20 is closer to the center of the disc than the innermost turn of the groove to be formed on the record 15. The needle 42 on the arm 40 is therefore not in vertical alignment with the needle 31. Instead the needle 31 is at a greater radial distance from the center 9 than is the needle 42. The needle 42 is therefore always closer to the center pin 9 than is the needle 42. As a result it is possible to make a sound groove on a record 9 which is of a diameter larger than the diameter of the turn table or of a diameter larger than the outside diameter of the disc 18.

At 65 is indicated a standard type of electromagnetic sound pick-up which is mounted at the end of an arm 66 pivoted at 67 in the usual manner, whereby the present apparatus may be used for reproducing sound as well as for recording sound.

In compliance with the requirements of the patent statutes I have here shown and described a preferred embodiment of my invention. It is, however, to be understood that the invention is not limited to the precise construction here

shown, the same being merely illustrative of the principles of the invention.

What I consider new and desire to secure by Letters Patent is:

1. In an apparatus for recording sound on a disc type record, a turn table having a record receiving surface on one side thereof and a spiral guiding groove on the opposite side, a support mounted for turning about an axis parallel to but spaced from the axis of the turn table, said support including a portion movable to a position overlying the table, a record impressing head pivoted on said support at said overlying portion for movement towards and away from the record receiving surface, a guiding arm pivoted on said support for movement towards and away from the spiral guiding groove, said arm having guiding means movable into and out of engagement with the groove by pivotal movement of said arm on said support, spring means urging the guiding means towards the groove, said guiding means moving in said spiral groove upon rotation of the turn table and being moved by the spiral to move said arm and said support to effect a movement of the head corresponding to the movement of the guiding means in the spiral groove, and a member rigid with the record impressing head and engaging the arm responsive to pivotal move-

ment of the head away from the record receiving surface for causing a corresponding pivotal movement of the arm to bring the guiding means out of said spiral groove.

5 2. In an apparatus for recording sound on a disc type record, a turn table having a record receiving surface on one side thereof and a spiral guiding groove on the opposite side thereof, a support mounted for turning about an axis parallel to but spaced from the axis of the turn table, a record impressing head pivoted on said support for movement towards and away from the record receiving surface, a forked member pivoted on the support and embracing the turn table and having groove engaging means at the lower tine thereof, spring means urging the groove engaging means of the forked member into engagement with the guiding groove on the turn table, said record impressing head including means rigid therewith and engaging the upper tine of the forked member for moving the upper tine of the forked member downward upon pivotal movement of the head away from the turn table whereby such pivotal movement of the head causes the lower tine to move downwardly and disengage the guiding groove engaging means from the groove.
